CONVEYOR RECEPTACLE FOR CARRYING
SOILED WARE IN A DISHWASHING
MACHINE

Erik O. Vilen, La Grange Park, Ill., assignor to
G. S. Blakeslee and Company, Cicero, Ill.

Filed Dec. 20, 1972, Ser. No. 316,698

Term of patent 14 years

Int. Cl. D15—99

U.S. Cl. D55—1 C

Fig. 6.

Fig. 5

Fig. 8

Fig. 7

Fig. 9

FIG. 1 is a front perspective view of a conveyor receptacle for carrying soiled ware in a dishwashing machine showing my design;

FIG. 2 is a top plan view of FIG. 1;

FIG. 3 is a side view of FIG. 1, taken from the right side thereof;

FIG. 4 is a bottom plan view of FIG. 1;

FIG. 5 is a front elevational view of my design;

FIG. 6 is a rear elevational view of my design;

FIG. 7 is a cross sectional view taken along the line 7—7 of FIG. 3 and looking in the direction of the arrows;

FIG. 8 is a cross sectional view taken along the line 8—8 of FIG. 3 and looking in the direction of the arrows; and

FIG. 9 is a cross sectional view taken along the line 9—9 of FIG. 3 and looking in the direction of the arrows. I claim:

The ornamental design for a conveyor receptacle for carrying soiled ware in a dishwashing machine, substantially as shown and described.
